[57] CLAIM

The ornamental design for a snow removal device, substantially as shown and described.

DESCRIPTION

FIG. 1 is a rear elevational view of a snow removal device, showing my new design;

FIG. 2 is a side elevational view thereof;

FIG. 3 is a front elevational view thereof;

FIG. 4 is an elevational view of the side opposite that shown in FIG. 2;

FIG. 5 is a bottom plan view thereof;

FIG. 6 is a top plan view thereof.

The handle has been shown fragmentarily in FIGS. 1-4 for ease of illustration and to indicate indeterminate length.
